E. E. MURPHY.
CARBONATING APPARATUS.

(Application filed Nov. 27, 1899.)

(No. Model.)

UNITED STATES PATENT OFFICE.

EDWARD E. MURPHY, OF SOMERVILLE, MASSACHUSETTS, ASSIGNOR TO
THE NEW ERA CARBONATOR COMPANY, OF CHARLESTOWN, WEST
VIRGINIA.

CARBONATING APPARATUS.

SPECIFICATION forming part of Letters Patent No. 658,798, dated October 2, 1900.

Application filed November 27, 1899. Serial No. 738,340. (No model.)

To all whom it may concern:

Be it known that I, EDWARD E. MURPHY, of Somerville, in the county of Middlesex and State of Massachusetts, have invented certain new and useful Improvements in Carbonating Apparatus, of which the following is a specification.

This invention relates to apparatus for carbonating water or other liquids.

10 The object of this invention is to provide a simple and efficient automatic apparatus which shall produce a thorough mechanical combination of the liquid and the carbonic-acid or other gas and in which the carbonating operation is controlled directly by the accumulation of the carbonated liquid, automatically ceasing when a predetermined quantity has been accumulated and automatically starting when the accumulation is 20 reduced.

My invention consists of certain novel features hereinafter described, and particularly pointed out in the claims.

In the accompanying drawings, which illustrate a construction embodying my invention, Figure 1 is a vertical sectional view of an apparatus embodying my invention, with the lower part of the storage-reservoir in full lines. Fig. 2 is a cross-sectional view through 30 the induction-head hereinafter described.

Like letters of reference refer to like parts throughout both views.

A represents a reservoir or receptacle for the carbonated liquid produced by the apparatus to be described. A suitable outlet distributing-pipe B extends down into said reservoir and is connected at its upper end to the outlet-passage B' in the coupling C, which is screwed into the top of the reservoir A, with 35 a suitable bushing C' between the top of the reservoir and the annular flange C² on said coupling. This passage B' communicates with the passage B² of the chamber B³, which is screwed into the coupling C at C³. The 40 passage B² communicates with the outlet B⁶ of said chamber, and communication between said passage B² and the outlet B⁶ is controlled by the valve B⁴, having a suitable operating-handle B⁵. Into the top of the coupling C is 45 screwed the valve-casing E', having a passage 50

D, controlled by the valve E, having a suitable operating-handle E². This passage communicates with the passage D' in the coupling C, and through said passage the liquid and gas mixed in the mixing-chamber pass to the storage-reservoir A. In the upper end of the valve-casing E' is screwed the lower end of the tube F, on which is screw-threaded at its upper end the spray-head H. In the upper part of said spray-head H is located the adjustable spray-nozzle I, having a series of perforations J, and said nozzle is supported in said head by resting in the upper end of the induction-head G', and supported in said nozzle is the strainer L. On the upper ends of said spray-head and nozzle is an annular packing M, of any suitable material and on which rests the flange M' of the water-inlet pipe M², and to said pipe M² is secured a globe-valve M³, having a suitable operating-handle M⁴, and communicating with said globe-valve M³ is a pipe N, having a suitable check-valve N', and said pipe is connected to a suitable source of water under high pressure. Over said flange M' is located the pipe N², which is screw-threaded around the head H and holds the globe-valve and water-inlet pipe in fixed position, as shown. Located on one side of the spray-head H is a nose O, communicating with the interior of said head and having an inlet-passage O' for the gas-supply and controlled by the valve O², having a suitable flexible face to adapt itself readily to its seat, and acting against said valve is a coiled spring O³, adapted to assist in operating the valve O² to close the passage O' as the apparatus fills with water. The cap O⁴ is screwed into the top of the nose O and has an opening in which the upper end of the stem of the valve O² moves, and against said cap rests the upper end of said spring O³. The valve E is for the purpose of shutting off communication between the mixing-chamber G, which is screwed on the lower end of the head G', and the reservoir A at any time when desired without interfering with the distribution of the carbonated liquid from the reservoir A.

The head G' is threaded at its upper end and screwed into the head H, and its lower end is also threaded, and to it is secured the

mixing-chamber G, as above stated. The induction-head G' is provided with four radial passages G² and the vertical central passage G³, which opens at its lower end into the chamber G, and its upper end communicates with the water-inlet through the perforations J. In the chamber G between the lower end of the head H and the cap G⁴, secured to the lower end of said chamber, there is located 10 the metallic sponge G⁵, composed of layers of wire-cloth, and by means of which the liquid and gas are minutely subdivided in order to facilitate their mechanical combination, and said sponge is held in a compact body by the 15 head G' and the cap G⁴. The mixing-chamber G is located within the tube F and is of smaller diameter than said tube to provide between them a passage G⁶ to allow the upward circulation of any excess of gas which 20 may pass down through the chamber G⁵ and which has not become mechanically mixed with the water.

The gas passing up through the passage G⁶ will pass into the radial passages G² of the 25 induction-head G' and meet the incoming water from the nozzle I and pass down into the chamber G. By this arrangement the churning of the gas and liquid takes place, so as to produce a proper intermixture of the two, 30 and any excess of gas returns and is brought into contact with the entering liquid, so that the carbonated liquid passing down through the passages D and D' into the reservoir A is properly intermixed.

35 In operation the liquid-supply pipe is connected to a high-pressure pipe under from one hundred and seventy-five to two hundred pounds pressure, and the gas-supply is connected to a gas-supply tank of, say, one hundred and twenty-five to one hundred and fifty pounds pressure. To prepare the apparatus for actual use, gas is first supplied through the passage O' and drives out all the air from the apparatus through the pipe B and the 40 outlet B', after which the valve B⁴ is shut off to close the outlet, and the gas is allowed to reach the pressure required. Water or other liquid is then admitted through the water-inlet N under the pressure above stated, which 45 is above the gas-pressure, and passes through the inlet I and head G', and the liquid being cut up by the sponge G⁵ at once causes the absorption of the gas in the chamber G on the passage of the liquid to the reservoir until 50 the apparatus is entirely filled with carbonated liquid up to the perforations J in the nozzle I. Now when the carbonated liquid is drawn off through the pipe B, the spray-nozzle I being so constructed as to retard the 55 admission of water, the carbonated liquid is drawn off faster than the same amount of water can be supplied in the same period of time through said nozzle, thereby providing room for the entrance of more new gas, which 60 enters by the opening of the valve O², which valve is opened on account of the gas-pressure behind it, which is then greater than

the pressure within the tube F, which pressure at that instant has been reduced by the drawing off of the carbonated liquid. Now 70 the water continuing to flow in through the nozzle I produces a greater pressure than the pressure of the gas admitted to the mixing-chamber by the drawing off of the carbonated liquid and closes the valve O² before the water-lever has reached said valve, which remains closed as the water rises and fills the tube, and the valve is maintained in its closed position by means of the spring O³ and the rising water and consequent pressure in the 80 chamber F as said chamber fills.

The mixing-chamber G is of much less diameter than the reservoir A, so that by partially or entirely emptying said chamber the reduction of pressure, owing to the reduction 85 of volume, will cause the admission of new gas by reason of the gas-pressure being sufficiently great to open the valve O² and pass into the chamber G. As the water continues to flow in through the nozzle it passes down 90 into the chamber G and mixes with the gas previously admitted to said chamber, and as the volume of water increases the pressure increases and closes the gas-valve O². As the chamber G gradually fills the increase in volume increases the pressure, and thereby closes the valve O² as soon as the pressure exceeds the gas-pressure. The admission of the gas to the chamber G is not due to the flow of water into said mixing-chamber; but its admission is controlled by the withdrawal of a 95 certain volume of carbonated liquid, which causes a reduction of pressure in the mixing-chamber below the initial gas-pressure, so that the gas under its own pressure passes into the 100 mixing-chamber at that instant, where it is mixed with the water passing down through said sponge contained in the mixing-chamber.

As previously stated, any excess of gas which may pass with the carbonated liquid from the bottom of the chamber G will leave 110 said carbonated liquid and circulate up through the passage G⁶ and will be drawn into the head G' through the passages G² by the induction of the inflowing water and comes into 115 contact with a fresh supply of water, so that in this manner the gas is utilized and no excess passes down in the storage-reservoir, as a certain volume of water takes up a certain volume of gas, and any excess of gas passes 120 up and is utilized by coming in contact with a fresh supply of water and mixing therewith. In this apparatus the original gas coming through the passage O' is fed by its own pressure into the mixing-chamber G, while any 125 excess of gas passing from the bottom of the chamber is drawn up by the induction of the inflowing water. The excess of gas passes up because it is lighter than the water.

The check-valve N' is for the purpose of 130 preventing loss of gas in the event of a break in the liquid-supply pipe.

The valve P, having a suitable handle P', controls the air-outlet P², through which air

is allowed to escape from time to time by operating the valve P.

I do not limit myself to the arrangement and construction shown, as the same may be varied without departing from the spirit of my invention.

Having thus ascertained the nature of my invention and set forth a construction embodying the same, what I claim as new, and desire to secure by Letters Patent of the United States, is—

1. In a carbonating apparatus, a liquid-inlet pipe for supplying liquid under pressure, a gas-inlet pipe for supplying gas under less pressure than that on the liquid, a mixing-chamber for the gas and liquid in constant open communication with the liquid-supply under initial liquid-pressure and normally filled with gas and liquid, a valve normally closing said gas-inlet pipe by the pressure in said mixing-chamber and adapted to open automatically by the pressure of the gas upon a reduction of pressure in the mixing-chamber below the gas-pressure to admit the gas which flows into the mixing-chamber by its own pressure independently of the flow of the liquid, means operating to allow the gas to fill the mixing-chamber before it is filled with the liquid, and a passage through which the excess of gas from the mixing-chamber returns to said mixing-chamber and is drawn therein by the induction of the inflowing liquid.

2. In a carbonating apparatus, a liquid-inlet pipe for supplying liquid under pressure, a gas-inlet pipe for supplying gas under less pressure than that on the liquid, a mixing-chamber for the gas and liquid in constant open communication with the liquid-supply under initial liquid-pressure and normally filled with gas and liquid, a valve normally closing said gas-inlet pipe by the pressure in said mixing-chamber and adapted to open automatically by the pressure of the gas upon a reduction of pressure in the mixing-chamber below the gas-pressure to admit the gas which flows into the mixing-chamber by its own pressure independently of the flow of the liquid, means for subdividing and mechanically combining the gas and liquid, means operating to allow the gas to fill the mixing-chamber before it is filled with the liquid, and a passage through which the excess of gas from the mixing-chamber returns to said mixing-chamber and is drawn therein by the induction of the inflowing liquid.

3. In a carbonating apparatus, a liquid-inlet pipe for supplying liquid under pressure, a gas-inlet pipe for supplying gas under less pressure than that on the liquid, a mixing-chamber for the gas and liquid in constant open communication with the liquid-supply under initial liquid-pressure and normally filled with gas and liquid, a valve normally closing said gas-inlet pipe by the pressure in said mixing-chamber and adapted to open

automatically by the pressure of the gas upon a reduction of pressure in the mixing-chamber below the gas-pressure to admit the gas which flows into the mixing-chamber by its own pressure independently of the flow of the liquid, means through which the gas and liquid are forced under pressure for subdividing and mechanically combining the same, means operating to allow the gas to fill the mixing-chamber before it is filled with the liquid, and a passage through which the excess of gas from the mixing-chamber returns to said mixing-chamber and is drawn therein by the induction of the inflowing liquid.

4. In a carbonating apparatus, a liquid-inlet pipe for supplying liquid under pressure, a gas-inlet pipe for supplying gas under less pressure than that on the liquid, a mixing-chamber for the gas and liquid in constant open communication with the liquid-supply under initial liquid-pressure and normally filled with gas and liquid, a valve normally closing said gas-inlet pipe by the pressure in said mixing-chamber and adapted to open automatically by the pressure of the gas upon a reduction of pressure in the mixing-chamber below the gas-pressure to admit the gas which flows into the mixing-chamber by its own pressure independently of the flow of the liquid, a wire sponge through which the gas and liquid are forced under pressure for subdividing and mechanically combining the same, means operating to allow the gas to fill the mixing-chamber before it is filled with the liquid, and a passage through which the excess of gas from the mixing-chamber returns to said mixing-chamber and is drawn therein by the induction of the inflowing liquid.

5. In a carbonating apparatus, a liquid-inlet pipe for supplying liquid under pressure, a gas-inlet pipe for supplying gas under less pressure than that on the liquid, a mixing-chamber in constant open communication with the liquid-supply under initial liquid-pressure and normally filled with gas and liquid, a valve normally closing said gas-inlet pipe by the pressure in said chamber and adapted to open automatically by the pressure of the gas to admit the gas upon a reduction of the pressure in said chamber below the gas-pressure, means for retarding the flow of the liquid from the liquid-inlet pipe into the mixing-chamber to allow the gas to fill the mixing-chamber before it is filled with the liquid, and a passage through which the excess of gas from the mixing-chamber returns to said mixing-chamber and is drawn therein by the induction of the inflowing liquid.

6. In a carbonating apparatus, a liquid-inlet pipe for supplying liquid under pressure, a gas-inlet pipe for supplying gas under less pressure than that on the liquid, a mixing-chamber in constant open communication with the liquid-supply under initial liquid-

pressure and normally filled with gas and liquid, a valve normally closing said gas-inlet pipe by the pressure in said chamber and adapted to open automatically by the pressure of the gas to admit the gas upon a reduction of the pressure in said chamber below the gas-pressure means for retarding the flow of the liquid from the liquid-inlet pipe into the mixing-chamber, means in said mixing-chamber for subdividing and combining the gas and liquid, and a passage through which the excess of gas from the mixing-chamber returns to said mixing-chamber and is drawn therein by the induction of the inflowing liquid.

7. In a carbonating apparatus, a liquid-inlet pipe for supplying liquid under pressure, a gas-inlet pipe for supplying gas under less pressure than that on the liquid, a mixing-chamber in constant open communication with the liquid-supply under initial liquid-pressure and normally filled with gas and liquid, a valve normally closing said gas-inlet pipe by the pressure in said chamber and adapted to open automatically by the pressure of the gas to admit the gas upon a reduction of the pressure in said chamber below the gas-pressure, a nozzle having a restricted outlet to retard the flow of the liquid from the liquid-inlet pipe into the mixing-chamber, and a passage through which the excess of gas from the mixing-chamber returns to said mixing-chamber and is drawn therein by the induction of the inflowing liquid.

8. In a carbonating apparatus, a liquid-inlet pipe for supplying liquid under pressure, a gas-inlet pipe for supplying gas under less pressure than that on the liquid, a mixing-chamber in constant open communication with the liquid-supply under initial liquid-pressure and normally filled with gas and liquid, a valve normally closing said gas-inlet pipe by the pressure in said chamber and adapted to open automatically by the pressure of the gas to admit the gas upon a reduction of the pressure in said chamber below the gas-pressure, a nozzle having a restricted outlet to retard the flow of the liquid from the liquid-inlet pipe into the mixing-chamber, a strainer located in said nozzle and a passage through which the excess of gas from the mixing-chamber returns to said mixing-chamber and is drawn therein by the induction of the inflowing liquid.

9. In a carbonating apparatus, a liquid-inlet pipe for supplying liquid under pressure, a gas-inlet pipe for supplying gas under less pressure than that on the liquid, a mixing-chamber for the gas and liquid in constant open communication with the liquid-supply under initial liquid-pressure and normally filled with gas and liquid, a valve normally closing said gas-inlet pipe by the pressure in said mixing-chamber and adapted to open automatically by the pressure of the gas upon a reduction of pressure in the mixing-chamber below the gas-pressure to admit the gas

which flows into the mixing-chamber by its own pressure independently of the flow of the liquid, means operating to allow the gas to fill the mixing-chamber before it is filled with the liquid, a passage through which the excess of gas from the mixing-chamber returns to said mixing-chamber and is drawn therein by the induction of the inflowing liquid, and an induction-head through which the incoming gas and liquid pass into the mixing-chamber and through which the excess of gas passes into the mixing-chamber by the induction of the inflowing liquid.

10. In a carbonating apparatus, a liquid-inlet pipe for supplying liquid under pressure, a gas-inlet pipe for supplying gas under less pressure than that on the liquid, a mixing-chamber for the gas and liquid in constant open communication with the liquid-supply under initial liquid-pressure and normally filled with gas and liquid, a valve normally closing said gas-inlet pipe by the pressure in said mixing-chamber and adapted to open automatically by the pressure of the gas upon a reduction of the pressure in the mixing-chamber below the gas-pressure to admit the gas which flows into the mixing-chamber by its own pressure independently of the flow of the liquid, means operating to allow the gas to fill the mixing-chamber before it is filled with the liquid, a passage through which the excess of gas from the mixing-chamber returns to said mixing-chamber and is drawn therein by the induction of the inflowing liquid, an induction-head provided with radial passages through which the incoming gas and excess of gas pass into the mixing-chamber and provided with a vertical passage through which the incoming liquid passes to the liquid-chamber, and means for subdividing and combining the gas and liquid.

11. In a carbonating apparatus, a liquid-inlet pipe for supplying liquid under pressure, a gas-inlet pipe for supplying gas under less pressure than that on the liquid, a mixing-chamber for the gas and liquid in constant open communication with the liquid-supply under initial liquid-pressure and normally filled with gas and liquid, a valve normally closing said gas-inlet pipe by the pressure in said mixing-chamber and adapted to open automatically by the pressure of the gas upon a reduction of the pressure in the mixing-chamber below the gas-pressure to admit the gas which flows into the mixing-chamber by its own pressure independently of the flow of the liquid, means operating to allow the gas to fill the mixing-chamber before it is filled with the liquid, a passage through which the excess of gas from the mixing-chamber returns to said mixing-chamber and is drawn therein by the induction of the inflowing liquid, an induction-head provided with radial passages through which the incoming gas and excess of gas pass into the mixing-chamber and provided with a vertical passage through which the incoming liquid passes to the liquid-

chamber, and a wire sponge through which the gas and liquid are forced under pressure for subdividing and combining the same.

12. In a carbonating apparatus, a liquid-inlet pipe for supplying liquid under pressure, a gas inlet pipe for supplying gas under less pressure than that on the liquid, a mixing-chamber for the gas and liquid in constant open communication with the liquid-supply under initial liquid-pressure and normally filled with gas and liquid, a valve normally closing said gas-inlet pipe by the pressure in said mixing-chamber and adapted to open automatically by the pressure of the gas upon a reduction of the pressure in the mixing-chamber below the gas-pressure to admit the gas which flows into the mixing-chamber by its own pressure independently of the flow of the liquid, means for retarding the flow of the liquid from the liquid-inlet pipe into the mixing-chamber to allow the gas to fill the

mixing-chamber before it is filled with the liquid, a passage through which the excess of gas from the mixing-chamber returns to said mixing-chamber and is drawn therein ²⁵ by the induction of the inflowing liquid, an induction-head provided with radial passages through which the incoming gas and excess of gas pass into the mixing-chamber and provided with a vertical passage through ³⁰ which the incoming liquid passes to the liquid-chamber, and a wire sponge through which the gas and liquid are forced under pressure for subdividing and combining the same.

In testimony whereof I have signed my ³⁵ name to this specification, in the presence of two subscribing witnesses, this 16th day of November, A. D. 1899.

EDWARD E. MURPHY.
